E. GANSFRIED

SPRING SECURED SAFETY VALVE

Filed Dec. 17, 1925

Inventor,
Eugene Gansfried,
By his Attorney Julian J. Wittig

UNITED STATES PATENT OFFICE.

EUGENE GANSFRIED, OF BRONX, NEW YORK.

SPRING-SECURED SAFETY VALVE.

Application filed December 17, 1925. Serial No. 75,900.

This invention relates to improvement in gas fixtures and has reference to the improvement of gas cocks or valves to prevent accidental opening of gas service lines, particularly those related to gas stoves, ranges, heaters and the like.

The object being to provide a construction both simple and inexpensive to preclude the liability of children or the inexperienced inadvertently opening a gas supply control, such as a cock or valve.

A principal feature of my invention is the provision of means normally acting to prevent turning movement of the valve stem, which can be manipulated to open the gas supply only when considerable manual downward pressure is exerted on the operating handle after which the gas supply passage may be made free by a quarter turn of said handle.

A further feature resides in the two part construction of the valve proper, which comprises a valve sleeve tapered to coincide with its casing and revoluble therein and a stem slideable in said sleeve and revoluble with said sleeve in the casing.

Further objects and features incident in the particular construction of the parts of the structure will be hereinafter apparent in the specification taken in connection with the accompanying drawing, in which I have illustrated a preferred embodiment, in which drawing:—

Fig. 1 is a central section with the ports of the device closed.

Fig. 2 is a partial sectional elevation showing the ports open.

Fig. 3 is a cross section on the line 3—3 of Fig. 1, and

Fig. 4 is a cross section on the line 4—4 of Fig. 1.

Referring to the drawings, 10 indicates a valve casing and 11 and 12, its intake and outlet service pipes. The interior of the casing has the usual taper and is adapted to receive a correspondingly tapered valve sleeve 13 having a central bore 14, in which a valve stem 15 operates through the use of handle 16. A stop pin 17 is provided on the sleeve 13 and is adapted to engage a shoulder 18 on the valve casing to limit the swing of the handle. Stem 15 further is provided with oppositely extending pin 19, operating

in grooves 20, and locking pin 21, normally engaging slots 22 in the bottom of the casing, said casing, at the bottom, being closed by a threaded cap 23, to prevent leakage.

The stem is also formed with a port 24, normally ranging at a right angle to the service pipes 11 and 12, and the sleeve 13 also has a port 25, likewise normally closed and in vertical alignment with the port 24, but not in normal horizontal alignment therewith.

The valve stem 15, is urged upwardly by a heavy spring 25, causing the pin 21 to bottom in the casing slots 22, thus locking the valve parts against rotation under normal conditions.

When, however, the handle 16 is depressed against the action of spring 25, which is heavy enough to thwart a child's efforts to force the parts downwardly, the stem 15 is likewise depressed until the ports 24 and 25' register and the pin 21 is free of the slots 22 in the casing, when the valve parts 13 and 15 may be turned to cause the said registering parts to align with the service pipes 11 and 12 and complete the service line, as will be understood.

The same construction may be applied to the upper burner cocks or valves of a range or stove by changing the parts as will be apparent to those skilled in the art.

Various changes in the form, proportions, and minor details of my invention may be resorted to at will without departing from the spirit and scope thereof. Hence I consider myself entitled to all such variations as may lie within the terms of my claims.

What I claim as new, is:—

1. A safety cock for gas lines comprising, in combination, with the usual valve casing having a tapered interior and radial slots at the bottom thereof, a valve shell having a port normally ranging at a right angle to the service pipes and opposite grooves, opening at the top thereof, a valve stem having a handle, pins operating in said grooves, a port normally in vertical alignment with the port of the shell and above the same, and pins near the bottom thereof to engage the slots in said casing to normally lock the valve parts against rotation, means for urging the stem into the above named position to close the gas supply and means for

- depressing said stem to unlock said stem so that said stem and valve shell may be revolved for opening said supply.
2. In a safety cock for gas lines, in combination with a casing, a two part valve therein, one part being revoluble therein, the other part being slidable and revoluble within the first, both parts having ports vertically aligned but normally non-registering, sliding locking means between the valve parts, slidable locking means between the parts and the casing whereby when the inner part is depressed, the said ports are caused to register and the parts unlocked from the casing to permit the valve structure to be turned, so that the said ports are aligned with the service pipes to open the gas line.
3. A gas control device comprising a casing, a two part valve therein, consisting of a valve shell and a stem slidable therein and both revoluble within said casing, means for normally locking the valve parts against rotation, said valve being adapted to be un-
- locked by depressing one of said parts to permit the turning thereof to open the service line.
4. A gas control device comprising a casing, a two part valve, consisting of a valve shell and a stem slidable therein and both revoluble within said casing, means for normally locking the valve to the casing, and means for unlocking said valve to permit the turning thereof by depressing one of said parts, to open the service line.
5. A gas control device comprising a casing, a multiple part valve consisting of a valve shell and a stem slidable therein and both revoluble within said casing, normally locked against rotation and means, when one part of said valve is depressed, for unlocking said valve to permit of its turning to open the service line.

Signed at New York city in the county of New York and State of New York, December, A. D. 1925.

EUGENE GANSFRIED.
